4 Claims. (Cl. 242—27)

1

The present invention relates to winding machines and more particularly to a method and means for automatically initiating the winding operation on winding machines.

For the purpose of automatically initiating the winding operation on cop winding machines, it is known to insert the beginning of the winding thread into a revolving thread clamp wherefrom the thread passes to the thread carrier (bobbin body or bobbin tube). The beginning of the thread then forms a length of thread projecting out of the finished package. After termination of the winding operation this length of thread has to be severed from the bobbin still remaining in the machine by means of a cutting device and, after having been disengaged from the thread clamp, this length must be drawn off by means of a suction system provided on the machine. Alternatively, after its withdrawal from the thread clamp and after the removal of the bobbin from the machine, the said length of thread projecting out of the bobbin is torn off by hand, in order to bring the weft bobbin into a condition suitable for weaving purposes.

It is an object of the present invention to eliminate the disadvantages connected with the described subsequent removal of the length of thread projecting out of the bobbin. According to the invention, a length of thread from the beginning of the thread to be wound is placed into a revolving thread clamp which turns about the axis of the thread carrier at a reduced speed relatively to the speed of the thread carrier, whereby a traction is exerted on said length of thread by the thread windings forming on the leading thread carrier, said traction causing the length of thread to be pulled out of the thread clamp and wound into the package to be formed on the thread carrier. Said length of thread accordingly is invisibly fixed in the interior of the finished package.

The invention will now be described more fully with reference to the accompanying drawings illustrating, by way of example, an embodiment of a winding spindle and driving means therefore, 45 suitable for carrying out the invention.

In the drawings:

Fig. 1 is an axial section through the drive for the winding spindle and the thread clamp, and

Figs. 2 to 6 are perspective views illustrating the initial stages of the winding operation.

According to Fig. 1 the winding spindle 1 of a weft winding machine is mounted in a bearing sleeve 2, carrying at its rear end a cone disc 3, which serves for coupling the spindle with a drive

2

shaft (not shown) connected to the driving gear of the machine in any conventional manner. The bearing sleeve 2 extends through a bushing 4, which is mounted in a wall 5 of the machine frame. The rear end of the bushing 4 contains a needle bearing 6 supporting the bearing sleeve 2, while a ball bearing 7 serving for the same purpose is disposed in the front end of the bushing 4. The cage 8 of the ball bearing 7 is flanged at 8a to form an outer, enlarged cylindrical extension 8b, completely surrounding a ball bearing 9. A ring 10 is engaged over the winding spindle 1 and secured to it by means of a cross pin 11. The ring 10 forms a front abutment for the ball bearing 8, the inner race 9a of which abuts with its opposite end against one end of the inner race 7a of the ball bearing 7; the other end of this inner race 7a bears against a shoulder 2a formed on the bearing sleeve 2. At the front side of the ring 10, the winding spindle 1 carries a driving disc 12 having a friction coating 13 for engaging the correspondingly enlarged end of a weft bobbin A, which according to Figs. 2-6 is slipped on the spindle 1 for winding purposes. An outer sleeve 14 is secured to the cylindrical extension 8b of the ball bearing 8 and provided with a flange 14a at its outer end remote from the ball bearing 8; the flange 14a carries a small plate 15 fastened thereto at its center by a rivet 16. The small plate 15 is bent upwards at both ends, so as to form two thread clamping positions at the flange 14a of the sleeve 14.

During operation the cone disc 3 transmits its rotary movement unchanged to the winding spindle 1, and the inner race 9a of the ball bearing 7, rigidly secured to the bearing sleeve 2, likewise turns at the full speed of the winding spindle 1. The balls of the ball bearing 7 operate as planetary friction members, turning in the same direction as the spindle 1 and transmit their movement of rotation with considerable reduction, for example, at the rate of 1:2.5 with respect to the speed of the associated inner race 7a, by the intermediary of the ball cage 8 and the cylindrical extension 8b thereof, to the outer sleeve 14, which consequently has a speed correspondingly reduced with respect to the winding spindle 1. Accordingly, the winding spindle 1 rotates faster than the double thread clamp, formed by means of the small plate 15 at the outer sleeve 14.

Depending on the direction of rotation of the outer sleeve 14 the winding thread B (Figs. 2-6) is inserted with its free end (beginning of thread) 55 into one or the other of the two thread clamps

formed by the plate 15 on the outer sleeve 14 (threading sleeve). In the course of the operation the thread B is automatically wound on the thread carrier A rigidly held on the winding spindle 1 (Fig. 3). As soon as the thread B firmly adheres to the thread carrier A, because the first thread windings B₁ cross each other more or less frequently and also due to its adhesion force, the length of thread retained underneath the clamping plate 15, which length according to Fig. 4 falls behind in speed as the result of the faster rotating thread carrier A, is automatically pulled out of the clamp by the traction exerted on the thread, so that the condition shown in Fig. 5 is brought about. This length of thread, i. e. the beginning of the thread, according to Fig. 6, is then wound around the thread carrier A and enveloped within the produced winding or package B₂. Any discard or waste of thread is avoided in the described, completely automatic winding operation.

The drive for the revolving thread clamp 15, 14a, of course, may also be effected in any other manner than by a ball—or other planetary drive, as for instance over a gear wheel—or belt drive, in order to obtain the desired difference in speed between the bobbin spindle and the thread clamp or the advancing of the thread carrier relatively to the thread clamp, without departing from the spirit of the invention or the scope of the appended claims.

Accordingly, there has been provided in accordance with the present invention a winding machine having a winding spindle, a revolving thread clamp arranged to turn about the axis of said winding spindle and adapted to engage a length of thread from the beginning of the thread to be wound on said thread carrier, a common driving member for said spindle and thread clamp, and movement transmission means operating to turn said thread clamp with a smaller speed than said winding spindle, whereby the length of thread engaged in said thread clamp is automatically pulled out of the clamp by the thread carrier and wound into the package to be formed on the thread carrier.

Having thus described the invention, what is

claimed as new and desired to be secured by Letters Patent, is:

1. The method of automatically initiating the winding operation on winding machines having rotating thread carriers, which consists in placing a length of thread from the beginning of the thread to be wound into a revolving thread clamp, and turning the thread clamp about the axis of the revolving thread carrier at a reduced speed with respect to the speed of the thread carrier, whereby a traction is exerted on said length of thread by the thread windings forming on the thread carrier, said traction causing the length of thread to be pulled out of the thread clamp and wound into the package to be formed on the thread carrier.

2. In a winding machine, a winding spindle, a package receiving thread carrier engaged on the winding spindle, a revolving thread clamp ar-

20 ranged to turn about the axis of said winding spindle and adapted to engage a length of thread from the beginning of the thread to be wound on said thread carrier, a common driving member for said spindle and thread clamp, and movement transmission means operating to turn said thread clamp with a smaller speed than said winding spindle, whereby the length of thread engaged in said thread clamp is automatically pulled out of the clamp by the thread carrier and wound into the package to be formed on the thread carrier.

3. A winding machine as claimed in claim 2, wherein said movement transmission means includes a planetary motion train imparting a reduced speed to said revolving thread clamp.

4. A winding machine as claimed in claim 2, wherein said movement transmission means includes planetary friction ball gearing for driving said revolving thread clamp at reduced speed with respect to the speed of said thread carrier.
